Primary Examiner — Christian P. McLean*Assistant Examiner* — Jessica Lynn Devilbiss(74) *Attorney, Agent, or Firm* — Nitin Kaushik(57) **CLAIM**

The ornamental design for a flying disc, as shown and described.

DESCRIPTION

FIG. 1 is a front perspective view of a flying disc, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the flying disc, which form no part of the claimed design. The dash-dot-dash broken lines illustrate the periphery of the enlarged views of the flying disc and form no part of the claimed design.

1 Claim, 9 Drawing Sheets(56)
